UNITED STATES PATENT OFFICE.

LEVI K. FULLER, OF BRATTLEBOROUGH, VERMONT, ASSIGNOR TO J. ESTEY & CO., OF SAME PLACE.

DESIGN FOR AN ORGAN-CASE.

Specification forming part of Design No. 7,199, dated February 24, 1874; application filed January 26, 1874.
[Term of Patent 14 years.]

To all whom it may concern:

Be it known that I, LEVI K. FULLER, of Brattleborough, in the county of Windham and State of Vermont, have invented a Design for an Organ-Case, of which the following is a specification:

The accompanying photographs fully illustrate the nature of my design, which relates to folding organ-cases.

The upper portions of the case are supported upon an open rectangular base, A, which encloses the pedals a a, and the back is formed by the leaf D. From the ends of the base A arise the brackets C C, which extend to the upper portion B of the case.

The front edges of the brackets present an ornamental curved outline, while the back edges are straight, as shown. The corners of the ends of the base and the corners of the leaf E and upper chest B are ornamented.

What I claim as my invention is—

The design for an organ-case, substantially as shown and described.

In witness whereof I have hereunto signed my name in the presence of two subscribing witnesses.

LEVI K. FULLER.
